UNITED STATES PATENT OFFICE.

JAMES L. HAVEN, OF CINCINNATI, OHIO.

DESIGN FOR A CASTER.

Specification forming part of Design No. 5,148, dated August 1, 1871.

To all whom it may concern:

Be it known that I, JAMES L. HAVEN, of Cincinnati, in the county of Hamilton and State of Ohio, have invented and produced a new and original Design for a Caster, of which the following is a specification:

The subject of my design is a furniture-caster, having the conformation represented in the accompanying perspective view, with a wedge-shaped or tapering fin projecting from either side or cheek.

I claim as my invention—
The design for a furniture-caster, as herein represented and specified.

In testimony of which invention I hereunto set my hand.

JAMES L. HAVEN.

Witnesses:

GEO. H. KNIGHT,
JAMES H. LAYMAN.
